CLAIM

The ornamental design for a portable electric drywall cutout tool, as shown.

DESCRIPTION

FIG. 1 is a perspective view of a portable electric drywall cutout tool showing our new design;

FIG. 2 is a top plan view thereof;

FIG. 3 is a front elevational view thereof;

FIG. 4 is a rear elevational view thereof;

FIG. 5 is a left side elevational view thereof;

FIG. 6 is a right side elevational view thereof; and,

FIG. 7 is a bottom plan view thereof.

The Makita trademark which forms a part of the claimed design is a registered trademark of Makita Corporation.
